FOOTBALL GAME BOARD WITH CONTROL RODS

Donald Huffman, Westmount, Montreal, Canada, assignor
to Coleco Industries, Inc., Hartford, Conn.

Filed Jan. 26, 1973, Ser. No. 326,760

Term of patent 14 years

Int. Cl. D21—01

U.S. Cl. D34—5 FG

FIG. 2

FIG. 3

FIG. 4

FIG. 5

FIG. 6

FIG. 7

FIG. 1 is a perspective view of a football game board with control rods showing the new design to a scale somewhat enlarged from that of the remaining figures;

FIG. 2 is an end elevational view thereof;

FIG. 3 is a plan view thereof;

FIG. 4 is an elevational view of the end opposite to that illustrated in FIG. 2;

FIG. 5 is a side elevational view;

FIG. 6 is an elevational view of the opposite side; and

FIG. 7 is a bottom view thereof.

I claim:

The ornamental design for a football game board with control rods, as shown.
